UNITED STATES PATENT OFFICE.

FRANK L. SAMPSON, OF BALDWINSVILLE, NEW YORK, ASSIGNOR TO THE WIRE GOODS COMPANY, OF WORCESTER, MASSACHUSETTS.

TROUSERS-STRETCHER.

SPECIFICATION forming part of Letters Patent No. 593,609, dated November 16, 1897.

Application filed November 4, 1896. Serial No. 611,059. (No model.)

To all whom it may concern:

Be it known that I, FRANK L. SAMPSON, a citizen of the United States, residing at Baldwinsville, in the county of Onondaga and State of New York, have invented certain new and useful Improvements in Trousers-Stretchers; and I do hereby declare the following to be a full, clear, and exact description of the invention, such as will enable others skilled in the art to which it appertains to make and use the same.

This invention relates to improvements in trousers-stretchers; and it consists of certain novel constructions, combinations, and arrangements of parts, all of which will be hereinafter more fully described and claimed.

In the accompanying drawings, forming a part of this specification, Figure 1 represents a side elevation of a pair of trousers suspended by means of my improved hanger. Fig. 2 represents an enlarged perspective view of my said improved hanger, and Fig. 3 a side elevation of the same.

A in the drawings represents the trousers, and B my improved hanger and stretcher. Said hanger and stretcher is composed of a single piece of wire and comprises a central spring-coil b , extended curved ends b' , b' , spring-arms b^2 , and clamping-rings b^3 . The 30 said extended ends b' are bent upward and formed into eyes b^4 , then downward upon themselves again in opposite directions, forming arms b^2 and curved hooks b^5 , b^5 , corresponding with the curved portions b^6 , b^6 . The 35 tension of the respective arms b' and b^2 is such as to keep them normally separated, but when the said rings b^3 are forced down the said arms and lower ends are brought firmly together and clamp any article that is between 40 them securely in place. The said arms b' are so bent as to bring the hook end b^5 upon one side into alinement with the loop b^6 upon the opposite side.

When this device is to be applied to a pair 45 of trousers, the same are first folded with the creases in the proper position and the rings b^3 slipped upward until they contact with the eyes b^4 . One of the curved portions b^6 on one side and the hook end b^5 upon the opposite 50 side is then slipped into one trousers-leg and the remaining hook end b^5 and bend b^6 into the other trousers-leg. To accomplish this, the said extended arms b' , carrying the arms

b^2 , must be forced toward each other, thus putting the coiled spring b under tension. 55 When the pressure upon said arms b' is relaxed, they spring outward against the trousers and said arms fall into the creases of the same and stretch the lower portions of said trousers taut. After the arms b' and b^2 are 60 in proper position the rings b^3 are slipped downward, thus tightening the arms upon the trousers and clasping them firmly in position.

It will be observed from the foregoing description that when a pair of trousers are so 65 suspended the full weight of the garment tends to straighten the legs and remove all creases or bagging from the knee portions. This tendency to remove the creases may be increased, if so desired, by slightly dampening 70 the garment. It will also be observed that as this device is constructed of a single piece of wire it may be manufactured very cheaply and be placed upon the market at a very low figure. 75

Having thus described my invention, what I claim as new, and desire to secure by Letters Patent, is—

1. A trousers-stretcher comprising a single piece of wire formed into a spring-coil, spring-loops pendent from said coil, spring-eyes at the tops of said loops, and pendent spring-arms having inwardly-turned lower ends and lying normally beside said loops and connected to the eyes formed at the upper ends 85 of the same, and rings mounted on said pendent loops and arms respectively, for drawing the same together to clamp the trousers-legs between them, substantially as described.

2. A trousers-stretcher, comprising a single 90 piece of wire formed into a spring-coil, spring-loops pendent from said coil, pendent spring-arms lying normally beside said loops and connected thereto at their upper ends, and rings embracing said loops and said arms for 95 drawing the same together to clamp the trousers-legs between them, substantially as described.

In testimony whereof I have signed this specification in the presence of two subscribing witnesses. 100

FRANK L. SAMPSON.
